UNITED STATES PATENT OFFICE.

ALOIS HELFENSTEIN, OF VIENNA, AUSTRIA, ASSIGNOR TO UNION CARBIDE COMPANY,
A CORPORATION OF VIRGINIA.

MULTIPLE-HEARTH ELECTRIC FURNACE.

1,223,278.

Specification of Letters Patent. Patented Apr. 17, 1917.

Application filed June 5, 1914. Serial No. 343,244.

To all whom it may concern:

Be it known that I, ALOIS HELFENSTEIN, a citizen of Switzerland, and a resident of Vienna, Austria, have invented an Improved and Novel Multiple-Hearth Electric Furnace, of which the following is a specification.

It is known in multiple-hearth electric furnaces of the before-mentioned kind to 10 arrange a charging bell or shaft around every electrode in order to effect a continuous charging operation around the same, and to draw off from said bell or shaft the furnace gases, or, if the furnace is closed, to 15 force said gases to collect below the furnace roof in order to be either burnt in the furnace or to be conducted away.

Especially in furnaces intended for large 20 outputs and having consequently a large consumption of raw materials, those arrangements entail complicated constructions, the superintendence and maintenance of which necessitate, in their turn, interruptions of work. Moreover, they require generally 25 special arrangements for packing the place where the electrode enters the bell, because an easy and good regulation of the electrodes is one of the chief conditions to be fulfilled in high-power plants. Furthermore, 30 broken electrodes can be removed from such bells but with difficulty, and exchanging the electrodes necessitates, with a closed bell, a great expense of time. Chiefly, however, the bell and hopper arrangements in 35 question do not answer the requirements if large quantities of mixed materials are to be treated, the difficulty being that, in high-power plants, the consumed quantities of mixture cannot be replaced quickly enough. 40 Finally, the bells and hoppers consist partly of iron and other metals; this fact however has an unfavorable influence upon the electric relations, especially the phase-displacement, because leakages of current from the 45 electrodes to those iron or metallic parts frequently occur.

The object of the present invention is to do away with the before-mentioned drawbacks and to allow of an ample charging of 50 the furnace, in connection with an ample, practically complete, drawing off of the fur-

nace gases, obviating at the same time complicated constructions around the electrodes. The invention consists in arranging upon the furnace shaft proper, in which the electric smelting process takes place, a charging shaft or hopper surrounding all electrodes of different polarity; said charging shaft or hopper may be formed by an upward extension of said furnace shaft proper. The 60 electrodes are then lodged, during the operation, completely within the mixture, for a length of 1.5-2.5 meters, as the case may be, and this column of mixture serves as a packing for those electrodes. Charging the common shaft is very easy, and may be effected in a continuous and mechanical way, and very few operators are required for it.

In order to obtain the gases developing during the process in a simple as well as 70 reliable and safe manner, gas outlet pipes, preferably provided with water jackets, are introduced around the electrodes through the side walls of the charging shaft into this latter, or tubes or bells are introduced 75 from above through the charging shaft down into the charge far enough to let the material lying over the lateral apertures or tube openings form a natural packing preventing the access of fresh air from above. There 80 may be a plurality of such gas conduits or exit openings in the side walls of the charging shaft, just as required, without rendering the furnace complicated or preventing proper and ample charging thereof. During 85 the operation attention is paid to whether or not small gas flames appear upon the mixture, or upon the charging material respectively, such flames indicating that the gas is not completely drawn off through the described conduits or openings, and consequently a certain small over-pressure exists in the furnace. This may be regulated easily and effectively by means of throttle-valves provided in said gas conduits, as is 90 all more fully described hereinafter.

The height of the charging shaft extension depends, of course, upon the process, especially, however, upon whether or not pulverulent or granulated material is made 100 use of. At any rate, the height of the charging shaft is so determined that the furnace

gases cool down as far as possible in the charge itself *i. e.* before they arrive at the exit opening, the purpose being to let the gases give off to the mixture their heat and eventually their reduction power.

The height should also be such as is necessary for packing the openings of the gas outlet conduits, and further to allow a certain length necessary for some spare material, according to the manner of charging the charging shaft. If, for instance, iron ores are to be reduced, an electrode of 2 meters' length will be completely covered by the charge and also the electrode socket will get down in course of time into the charge, as the electrode is consumed during the course of the process. If, however, the height of the normal working shaft of an electric raw iron furnace amounts, for instance, to about 1.5-2 meters, the height of the charging shaft forming the extension of the former will amount to about 1.5-3 meters or even more.

In order to prevent as far as possible leakage of the current from the electrodes to the mixture surrounding them, the electrodes, as well as their sockets, are electrically insulated as perfectly as possible by means of a suitable insulating material consisting, for instance, of asbestos which may be stiffened or reinforced by a sheet-metal sleeve. The length of the combined insulating material and sleeve is so chosen that the electrode sockets are protected to a height of at least 1 meter. The insulating material and the sleeve are rigidly connected with the electrode and are consumed with the latter in the furnace.

In order to prevent leakage of current from one electrode or electrode socket through the charge of the charging shaft to the next electrode, and to keep up service with the electrodes of the remaining phases if those of any one phase are to be exchanged, and to prevent air from finding access to the gas exit pipes of the working electrodes, partition walls are inserted in the common charging shaft between the electrodes of different polarity, said walls extending downwardly below said gas exit pipes. The said walls may be built up of fire-bricks, forming vaulted girds extending from one wall of the furnace to the other.

In order to make my invention more clear, I refer to the accompanying drawing which shows the subject matter of the invention applied to a three-phase furnace.

Figure 1 is a longitudinal section through the furnace, the plane of section being laid through the three electrodes and the parts being shown in the position they occupy during operation.

Fig. 2 is a cross section through the same furnace, in the plane of one bundle of the electrodes; and

Fig. 3 is a similar section, showing a some-

what different arrangement of the means for drawing off the gas.

a₁ a₂ a₃ are the three electrodes of different polarity, or the bundles of such electrodes respectively; *b* is the common reaction shaft and *c₁ c₂* is the common charging shaft, located just above the shaft *b*. The upper ends of the electrodes are provided with the sockets *f₁ f₂ f₃* serving for attaching the conductors, and each electrode and its socket have a common insulating sleeve *g₁ g₂ g₃*.

Between every two of the reaction hearths is arranged, in the charging shaft, a partition wall *h₁* or *h₂* respectively, extending preferably down into the reaction space and consisting each of, or forming each, a fire-proof girth.

The gas is drawn off either through tubes *i₁ i₂* (Fig. 1) inserted into the wall of the charging shaft and provided with water jackets (the regulation being effected by throttle valves *d*), or by means of tubes *m₁ m₂* (Fig. 3) extending from above into the common charging shaft and having enlarged ends. The arrangement of these pipes may be such that a regulation with respect to the depth of entrance of the gases during operation is rendered possible, for instance, by means of a chain and a counter-weight, as shown in Fig. 3.

The collected gases pass over into the conduits *n₁ n₂* which, according to the process, may serve also as combustion or as condensation pipes, or they may be constructed in such a manner that the gases are conducted away through the same without being burnt, or that they are burnt in the presence of or together with a suitable supply of air.

The before-described improved furnace is intended especially for the production of heavy metals, alloys having iron as a component and volatile metals and their oxides, such as zinc and oxid of zinc; also other electro-thermic reactions may be carried out with its aid.

Having now described my invention, what I desire to secure by Letters Patent of the United States is:

1. In a multiple-hearth electric furnace provided with vertical electrodes of different polarity arranged one over each smelting hearth, the combination, with the reaction shaft of the furnace which is adapted to receive all electrodes of different polarity, of a charging shaft arranged over said reaction shaft, and gas outlet pipes extending into the material contained in said charging shaft down to a depth where the charging material above the pipe entrances is capable of serving as a packing to prevent the access of fresh air, said electrodes extending through the said charging shaft, for the purpose as described.

2. In a multiple-hearth electric furnace

provided with vertical electrodes of different polarity arranged one over each smelting hearth, the combination, with the reaction shaft of the furnace which is adapted to receive all electrodes of different polarity, of a charging shaft arranged over said reaction shaft, and gas outlet pipes reaching from above through the upper layer of the charging material into the charging shaft, 10 said upper layer being adapted to exclude the outer air, and said electrodes extending vertically from above through said charging shaft into the reaction shaft, for the purpose as described.

15 3. In a multiple-hearth electric furnace provided with vertical electrodes of different polarity arranged one over each smelting hearth, the combination, with the reaction shaft of the furnace which is adapted to receive all electrodes of different polarity, of a charging shaft arranged over said reaction shaft, and electrical insulators each inclosing an electrode bundle and its sockets, the length of each cover in upward 25 direction being such as to prevent the charge from coming in contact with the sockets, even when the electrodes have been completely consumed.

4. In a multiple-hearth electric furnace 30 provided with vertical electrodes of different polarity arranged one over each smelting hearth, the combination, with the reaction shaft of the furnace which is adapted to receive all electrodes of different polarity, of a charging shaft arranged over said reaction shaft, gas outlet conduits communicating with the interior of said charging shaft at a depth where the charging material above the entrance openings of said 40 conduits will prevent the access of air, and electrical insulators inclosing each an electrode bundle and its sockets, the length of each cover in upward direction being such as to prevent the charge from coming in 45 contact with the sockets, even when the electrodes have been completely consumed.

5. In a multiple-hearth electric furnace provided with vertical electrodes of different polarity arranged one over each smelting 50 hearth, the combination, with the reaction shaft of the furnace which is adapted to receive all electrodes of different polarity, of a charging shaft arranged over said reaction shaft, partition walls arranged 55 each between two electrodes of different polarity and above the working zone of said electrode, and electrical insulators each inclosing an electrode bundle and its sockets, the length of each cover in upward direction being such as to prevent the charge 60 from coming in contact with the sockets, even when the electrodes have been completely consumed.

6. In an electric furnace, a smelting 65 hearth, a charging-shaft thereover, and elec-

trodes extending downward through the charging-shaft to said smelting-hearth, the portions of said electrodes in the charging-shaft being electrically insulated within the charge.

7. In an electric furnace, a smelting-hearth, a charging-shaft thereover, and adjustable electrodes extending downward through the charging-shaft to said smelting-hearth, the portions of said electrodes in the charging-shaft being protected within the charge by electrical insulation consumable therewith.

8. In an electric furnace, a smelting-hearth, a charging-shaft thereover, and adjustable electrodes extending downward through the charging-shaft to said smelting-hearth, the portions of said electrodes in the charging-shaft being protected within the charge by electrical insulation consisting of metal-reinforced asbestos.

9. In an electric furnace, a smelting-hearth, a charging-shaft thereover, adjustable electrodes extending downward through the charging-shaft to said smelting-hearth, 90 electrode-holders movable with their electrodes through the charge, and casings for electrically insulating said electrodes and said holders for protecting them within the charge, the insulation being consumable with the electrodes.

10. In an electric furnace, a smelting-hearth, a charging-shaft thereover, adjustable electrodes extending downward through the charging-shaft to said smelting-hearth, 100 electrode-holders movable with their electrodes through the charge, and casings for electrically insulating said electrodes and said holders for protecting them within the charge, said insulating casings comprising 105 asbestos jackets with reinforcing metal sleeves.

11. In an electric furnace, a smelting-hearth, a charging-shaft thereover, electrodes extending downward through the 110 charging-shaft to said smelting-hearth, means extending into the charge for withdrawing the gases therefrom and means for controlling the efflux of the gases.

12. In an electric furnace, a smelting-hearth, a charging-shaft thereover, electrodes extending downward through the charging-shaft to said smelting-hearth, and a gas outlet-pipe in said charging-shaft having its receiving-end in the body of the 120 charge.

13. In an electric furnace, a smelting-hearth, a charging-shaft thereover, electrodes extending downward through the charging-shaft to said smelting-hearth, and a gas outlet-pipe in said charging-shaft having a flaring receiving-end in the body of the charge.

14. In an electric furnace, a smelting-hearth, a charging-shaft thereover, elec-

trodes extending downward through the charging-shaft to said smelting-hearth, a gas outlet-pipe extending downwardly into said charging-shaft having its receiving-end
5 in the body of the charge, and means for adjusting the height of said receiving-end.

In testimony whereof I affix my signature in presence of two witnesses.

ALOIS HELFENSTEIN.
